UNITED STATES PATENT OFFICE

WILLIAM F. ZIMMERMANN, OF MAPLEWOOD, NEW JERSEY, ASSIGNOR TO GOULD & EBERHARDT, OF NEWARK, NEW JERSEY, A CORPORATION OF NEW JERSEY

GUIDE RAIL FOR SHAPING MACHINE WORKTABLES

Application filed January 9, 1925. Serial No. 1,384.

My invention relates to guide rails for shaping machines and particularly to guide rails wherein one rigidly mounted guide plate is provided for guiding the associated work table.

One object of my invention is to provide improved means for so mounting and securing the work table of a shaper to the cross rail thereof as to insure against any bending or bowing of the cross rail or any part thereof under heavy cuts by the tool carried on the reciprocating ram.

Another object of my invention is to provide a cross rail for supporting a work table on a shaper with a bearing and a guiding plate, the work table engaging guiding surfaces at the rear and at the bottom of the guide plate so that one securely and rigidly mounted plate serves for guiding the work table.

A further object of my invention is to provide a cross rail on a shaping machine with a guide plate that shall have guiding surfaces at the lower part and at the rear part thereof, the rear guiding surface being inclined towards the lower front part of the rail and the guiding surface at the lower part of the plate being inclined towards the upper rear part of the cross rail so that the weight of the work table resting on the cross rail will serve to tighten and hold the table more securely in position.

In a shaping machine, it is desirable and very essential to hold the work firmly and rigidly in position so that no giving or movement of the work will take place when heavy cuts are being effected. Trouble in this respect is often incurred by the reason of the bowing or the bending of the cross rail which is mounted on the main frame of the shaper and which carries the work table. Such bending of the cross rail is often effected by having the guiding surfaces for the work table too widely separated and by not providing a sufficiently rigid support for the guiding surfaces.

In a shaping machine provided with a guide rail constructed in accordance with my invention, the guiding surfaces for the movement of the work table along the cross rail

are positioned relatively close together and the bearing surface for the work table on the cross rail is positioned to insure rigid mounting of the table. The guide surfaces for the work table are so inclined as to insure tightening and more secure fastening of the table to the cross rail when heavy cuts are taken by the tool mounted on the reciprocating ram.

In a cross rail mechanism, constructed in accordance with my invention, the reducing of the distance between the two guiding surfaces for the work table is effected by forming such guiding surfaces at the top and at the bottom of a single guiding plate. Such guiding plate is preferably provided with a rectangular projection from the upper part thereof and the projection is engaged by a hook portion on the work table. The lower guiding surface is engaged by a projection from the work table. It is apparent that a single guide plate can be very rigidly mounted on the cross rail so as to insure against any bowing or bending tendency which will loosen the connection of the work table to the cross rail. The guiding surfaces for the work table are so positioned or inclined as to more securely fasten the table to the cross rail when the heavier cuts are being taken by the tool.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

In the accompanying drawings, Fig. 1 is a front elevational view of a shaper having a guide rail constructed in accordance with my invention. Fig. 2 is a detail view partially in section of the gib at the lower part of the guide plate. Fig. 3 is a sectional view along the line $x-x$ of Fig. 2. Fig. 4 is an

end view of the shaper shown in Fig. 1. Figs. 5 and 6 are sectional views illustrating the means for adjusting the gib located at the rear of the guide plate.

- 5 Referring to the accompanying drawings, a shaper 1 is provided with a main frame 2 and a reciprocating ram 3. The ram 3 is reciprocated on the main frame 2 in any suitable manner and carries a tool head 4. 10 The tool head 4 comprises a clapper-box 5 which carries a cutting tool 6. The stroke of the ram 3 is varied in any suitable and conventional manner and the position of the ram is controlled by means of a ram adjusting shaft 7. 15 A cross rail 8, which is mounted on the main frame 2, is raised and lowered by means of a screw shaft 9. The screw shaft 9, which is operated by means of a shaft 10 having a squared end, is adapted to be operated by a suitable crank handle. The cross rail 8 is provided with a guide plate 11 and a bearing plate 12. The guide plate 11 is provided with a rectangular projection 13 which has a flat surface 14 formed on the rear thereof. 20 The lower surface 15 of the guide plate 11 is inclined so as to make an acute angle with the front surface 16 of the plate. Such surface 15, as shown in Fig. 1 of the drawings, 25 is inclined towards the upper rear portion of the rail. The bearing plate 12 is provided with a single bearing surface 17. The guide plate 11 and the bearing plate 12 are preferably formed as an integral part of the body 30 portion of the cross rail. Between the guide plate 11 and the bearing plate 12 is mounted a screw shaft 18 for effecting movement of a work table 19 across the cross rail. The screw shaft 18 is provided with a squared end portion 20 which may be operated by a crank-handle. Although the screw shaft 18 may be 35 operated manually for effecting movement of the work table 19 across the cross rail, suitable mechanism comprising a cross feed shaft 40 22 and a cross feed head 22^a are provided for effecting automatic movement of the table. The cross rail 8 is operated on suitable guides 45 23 formed on the main frame 2 and is clamped to the main frame in any suitable manner.

- 50 The work table 19 preferably comprises a work supporting portion 24 and a base portion 25 which is secured to the cross rail 8. Suitable T-slots 26 are formed on the sides and the top of the work-supporting portion 24 for securing the work or any suitable work holding vise to the table. T-slots 27 are formed in the base 25, as best shown in Fig. 1 of the drawing. Such T-slots 27 serve not only as a means for connecting the work-supporting member to the base 25 but also serves as a means for supporting the work if it is desirable or convenient to dispense with the work-supporting portion 24.

- 55 A hook portion 28 is formed on the base 25 for engaging the guide rail 11, as shown in

Fig. 1 of the drawings. One surface of the hook portion 28 rests on the top of the guide rail 11 and another inclined surface 29 of the hook portion engages a gib member 30. The gib member 30 is mounted in position between the flat surface 14 on the rear of the guide plate 11 and the inclined surface 29 on the hook 28. It should be noted the gib 30 is wider at the top than at the bottom thereof, as shown in Figs. 1, 5 and 6 of the drawings. It should also be noted the inclined surface 29 on the hook 28 and the inclined surface on the gib project in a direction towards the lower front part of the cross rail. By so directing the inclined surfaces for guiding the table on the cross rail, it is apparent the pressure produced by a heavy cut does not tend to loosen the connection of the table to the cross rail but on the other hand tends to tighten and more securely hold the cross rail in position. Accordingly, the outer end of the table does not tend to lower or be forced down under extremely heavy cuts.

60 A projection 32 from the base 25 is provided with a surface 33 which is inclined in the same direction as the surface 15 which is formed on the bottom of the guide rail 11. A suitable gib 34 of the customary wedge type is positioned between the surface 15 on the guide plate and the surface 33 on the table. An adjusting screw 35, which is shown in Figs. 1, 2, 3 and 4 of the drawings, is provided for varying the position of the gib 34. The adjusting screw 35 is provided with a shoulder 36 which is fitted to a slot 37 in the gib for effecting movement of the gib in accordance with the movement of the screw. A nut 38, which is threadably connected to the screw 35 serves to lock the screw and also the 65 gib in any set position.

70 The position of the gib 30 is controlled by two holding screws 39 and two stop or limiting screws 40. The limiting or stop screws 40 are threadably connected to the hook portion 28 of the work table and engage the top surface of the gib 30, as best shown in Fig. 6 of the drawings. The holding screws 39 are rotatably mounted in the hook 28 and are threadably connected to the gib 30. The 75 screws 40 are operated for limiting the position of the gib and the screws 39 are operated for holding the gib firmly in engagement with holding screws 40.

75 In a cross rail constructed in accordance 80 with my invention it will be noted that the guiding surfaces for the work table are located respectively near the top and the bottom of one guide plate. Consequently such guiding surfaces are maintained in correct 85 relation to each other to maintain a rigid and steady support for the table on the cross rail. In many constructions heretofore proposed the guiding surfaces have been located on different guide plates. Such a construction, 90

however, has been found faulty under many operating conditions inasmuch as the guiding surfaces are somewhat widely separated and the top guiding plate tends to bow out in a horizontal plane under extremely heavy cutting operations. The bowing out of the top guide plates tends to loosen the connection of the table to the cross rail. As pointed out above the inclining of the surface of engagement between the gib 30 and hook 29 in a direction shown in Fig. 1 of the drawing serves to clamp the table securely to the cross rail when heavy cutting operations are being effected. When pressure is placed upon the work table the hook 28 is merely held more firmly and tighter to the gib 30 and the guide plate. The bearing surface 17 on the bearing plate 12 serves to take care of the downward pressure and to act as a fulcrum to assist in holding the gib 30.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention, and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:—

1. In a shaper having a reciprocating tool carrying ram, the combination comprising a cross rail having at its upper portion a single solid guide plate, said plate providing a rectangular portion projecting from the upper part thereof and a lower guide surface inclined upwardly and rearwardly relative to the front face thereof; a work table mounted on the cross rail, said work table being guided at the top and bottom part of said guide plate; and a feed mechanism for shifting said table along said rail, said feed mechanism being located wholly at one side of said single solid guide plate.

2. In a shaping machine, the combination comprising a cross-rail having at its upper portion a single solid guide plate providing adjacent its upper edge a substantially rectangular table supporting portion, and at its lower edge a table guide surface inclined upwardly and rearwardly relative to the front face thereof, said cross-rail also providing, at its lower portion, a vertical bearing plate; a work-table mounted on said cross-rail and having portions engaging respectively, said rectangular portion and said inclined guide surface to support the weight of said table and to prevent up-

ward and outward movement of the upper portion thereof, said table also having a thrust engagement with said vertical bearing plate to prevent inward movement of the lower portion of said table; and feed mechanism for shifting said table along said cross-rail, said feed mechanism being located wholly at one side of said single solid guide plate.

3. In a shaping machine, the combination comprising a cross-rail having at its upper portion a single solid guide plate providing adjacent its upper edge a substantially rectangular table supporting portion affording at its top a horizontal table supporting surface and at its rear a substantially vertical bearing surface, said guide plate also being provided at its lower edge with an upwardly and rearwardly inclined guide surface; a work-table supported upon said cross-rail and having a hook-portion extending over and downwardly behind the rectangular portion of said guide plate, said hook-portion being supported against downward and outward movement by said table supporting surface and said vertical bearing surface, said table also having a portion extending below and behind and cooperating with said upwardly and rearwardly inclined guide surface to prevent outward and upward movement of said table; a gib located between the rear vertical bearing surface of said rectangular portion and the hook-portion of said table; a second gib located between said upwardly and rearwardly inclined bearing surface and the cooperating portion of said table; and feed mechanism for said table located wholly at one side of said single solid guide plate.

4. In a shaping machine the combination comprising a cross-rail having at its upper portion a single solid guide plate, said plate providing a rectangular portion projecting from the upper part thereof and a lower guide surface inclined upwardly and rearwardly relative to the front face thereof, said cross-rail also providing, at its lower portion, a vertical bearing plate; a work-table mounted on said cross-rail and having a hook-portion extending over and downwardly behind the rectangular portion of said guide plate and a portion extending upwardly behind and cooperating with said inclined bearing surface, said table also having a portion bearing against the vertical bearing plate provided by said cross-rail; a gib arranged between the rear face of the rectangular portion of said single solid guide plate and that portion of the table extending downwardly therebehind, said gib being wider at the top than at the bottom thereof; means for adjusting said gib vertically; and feed mechanism for said table located wholly at one side of said single solid guide plate.

5. In a shaper, the combination comprising a frame; a cross-rail mounted thereon

and having an upper portion thereof comprising a single relatively narrow plate adapted solely to support a work-table and to prevent upward and outward movement thereof, said plate forming an upwardly projecting portion substantially rectangular in cross section and an upwardly and inwardly inclined guide surface at its lower edge; a work-table mounted on said cross rail and having a hook portion extending over and engaging the rear of said upwardly projecting portion and a portion extending upwardly behind and engaging said inclined guide surface; and feed mechanism, located wholly beneath said plate for moving said table along said cross rail.

6. In a shaper, the combination comprising a cross-rail having at its upper edge a single guide plate adapted solely to support a work-table and to prevent outward and upward movement thereof, and, at its lower edge, a vertically disposed thrust bearing plate adapted to prevent inward movement of a work-table, said guide plate having a portion projecting upwardly and affording, at its rear, a table bearing surface; an upwardly and inwardly inclined bearing surface at the lower edge of said guide plate; a work-table mounted on said cross rail; said table having, a lower portion bearing laterally on said thrust bearing plate, an upper portion, in the form of a hook, projecting over and downwardly behind and engaging the upwardly projecting portion of said guide plate, and an intermediate portion extending upwardly behind and in contact with said inclined bearing surface, the overhanging hook portion of said table having an undercut bearing surface inclined toward the lower front face of the cross-rail; and means located at one side of said single guide plate to feed said work-table along said cross-rail.

7. In a shaper having a reciprocating tool-carrying ram, the combination comprising a cross-rail including a single solid plate adjacent the upper edge thereof, the upper portion of said guide plate providing an upper substantially horizontal bearing surface and a rear substantially vertical bearing surface, said bearing surfaces serving wholly to support the weight of a work-table and to prevent outward movement of the upper portion thereof, said guide plate also affording, at its lower edge, a bearing surface adapted to prevent upward movement of the work-table and outward movement of the lower portion thereof; a work-table mounted on said plate in engagement with said bearing surfaces and movable along said rail; and a screw shaft located wholly at one side of said plate for moving the table along the rail.

8. In a shaper having a reciprocating tool-carrying ram and a work-table, the combination comprising a cross-rail having at its upper edge a solid undivided guide plate and at its lower edge a thrust bearing plate, said

guide plate affording, at its top, bottom and rear sides, bearing surfaces adapted respectively to support the weight of the work-table and to prevent outward and upward movement thereof and said thrust bearing plate preventing inward movement of the lower part of said table; and a screw shaft located wholly at one side of said guide plate and between the guide plate and said thrust bearing plate for moving the table along the rail.

In witness whereof, I have hereunto subscribed my name.

WILLIAM F. ZIMMERMANN.
